HAM PRODUCT

Andre Caunes, F 74-Langin,
par Bons-en-Chablais, France

Continuation-in-part of design application Ser. No. 18,800,
Aug. 22, 1969. This application Aug. 26, 1971, Ser.
No. 175,126

Claims priority, application France Mar. 7, 1969

Term of patent 14 years

Int. Cl. D1—04

U.S. Cl. D1—26

FIG. 1

FIG. 2

FIG. 1 is a perspective view of a ham product showing my new design; and

FIG. 2 is a perspective view of another embodiment of the ham product shown in FIG. 1.

The sides opposite those shown in each figure are identical to the corresponding opposite sides shown.

This application is a continuation in part of my application Ser. No. D. 18,800, filed Aug. 22, 1969 and now abandoned.

I claim:

The ornamental design for a ham product, substantially as shown and described.
